TICKET RACK

Conrad Genjack, North Vancouver, British Columbia, Canada

Application June 27, 1932. Serial No. 619,398

3 Claims. (Cl. 206—40.6)

My invention relates to improvements in ticket racks which are adapted to contain strip tickets such as are sold by purveyors of bread, milk and the like, the holder is adapted to support such tickets in a manner whereby a single ticket may be conveniently detached from any strip as may be desired, as will be more fully described in the following specification and shown in the accompanying drawing, in which:—

5 Fig. 1 is a general view of the invention arranged to support two strip tickets side by side.

Fig. 2 is a sectional view taken on the line 2—2 of Figure 1.

Fig. 3 is a general view of a modification arranged to support a plurality of strip tickets in superimposed relation.

Fig. 4 is a sectional view taken on the line 4—4 of Figure 3.

In the drawing like characters of reference 20 indicate corresponding parts in each figure.

The numeral 1 indicates generally a panel having nail holes 2 to facilitate its being secured to a wall surface. The panel is preferably formed with its marginal edges bent back upon themselves in closely formed corrugations 3 to define pairs of U-shaped guides 4 and 5, which are open towards the centre of the panel.

The centre portion of the panel is preferably bent to form a T-shaper rib 6, which defines a 30 pair of opposed U-shaper guides 7. These latter are complementary to the guides 4, and the rib is so formed as to lie below the plane of the guides 5.

The lower end of the panel 1 is outwardly 35 curved as at 8 and the width of the guides is slightly reduced for the purpose of disposing the lowermost of the tickets contained in the guides in a position convenient to discharge, and also to impede the free downward movement of said 40 tickets. A slot 9 is formed in the lower extremity of the panel between each pair of opposing guides which may, if desired, afford access to the lowermost ticket of each strip from the rear.

45 Extending between opposing guides at the lower extremity of the panel is a transverse member 10 which is slightly rounded on its underside as at 11, see Figure 2, and is provided on its front with a downwardly turned lip 12 to form a 50 straight edge against which the lowermost ticket may be freely severed from its strip.

In the modification shown in Figures 3 and 4, the panel is of single strip width and is provided with a plurality of opposing guides 13, 55 14, 15 and 16 respectively, which are of progressively decreasing length. The guides 13, 14 and 15 being outwardly turned at their lower extremities as at 17, 18 and 19 respectively to provide access to the lowermost tickets of the 60 strips therein. The guides 16 are preferably

spaced further apart than those indicated by the numerals 13, 14 and 15, so as to provide a holder of substantial width for a card 20 bearing advertising or other desired matter.

It will be obvious that the guides 4, 5, 7, 13, 14, 15 and 16 may be formed in any other manner than that described and that the slots 9 at the lower extremity may be omitted without departing from the spirit of the invention.

The device may be supplied by a producer to his customers, in which case he would utilize the guides 5 of the invention as shown in Figures 1 and 2, or the guides 16 of the device as shown in Figures 3 and 4, to display therein cards 21 or 20 respectively as an advertisement for his product and would sell to the customer strip tickets 22 having the usual transverse perforated lines 23 to divide the strip into separate tickets or units 24. A strip so bought is placed with its marginal edges in opposing guides, such as between the right hand guide 7 and the right hand guide 4, as shown in Figure 1, and is pressed downwardly until its lower extremity is disposed beneath the transverse member 10, so that when a single ticket is required the lower extremity of the strip is gripped by the thumb and finger and drawn downwardly until the lowermost ticket is clear of the panel, when a twisting movement will sever it from the strip. The strip tickets may also be moved to project the lowermost ticket by simply applying the finger tip to the strip and drawing it in a downward direction.

What I claim as my invention is:

1. A strip ticket holder comprising a pair of opposed guides spaced apart and adapted to support a strip ticket by its marginal edges, means adjacent one end of the guides against which the strip ticket is adapted to be severed, and means for impeding the free movement of the ticket along the guides.

2. A strip ticket holder comprising a panel supporting a pair of opposed guides between which a strip ticket is adapted to be supported by its marginal edges, said guides being outwardly turned to project beyond the general plane of the panel and a transverse member connecting the guides adjacent one end against which the strip ticket is adapted to be severed.

3. A strip ticket holder comprising a panel, a plurality of superimposed pairs of parallel guides carried by the panel, the lower end of such successive pair of guides terminating at a point above the corresponding end of the previous pair, each of said pair of guides being adapted to support a strip ticket by its marginal edges, and each pair of guides being outwardly turned to project from the general plane of the panel, and means associated with each pair of guides against which the ticket is adapted to be severed.
